[57] CLAIM

The ornamental design for a combined plumbing fixture bowl and cabinet, as shown and described.

DESCRIPTION

FIG. 1 is a perspective view taken from the top, front and left side of a combined plumbing fixture bowl and cabinet showing my new design;
 FIG. 2 is a front elevation thereof;
 FIG. 3 is a top plan view thereof;
 FIG. 4 is a bottom plan view thereof; and
 FIG. 5 is a left side elevation thereof, the right side is a mirror image of the left side shown.
